INTERLOCK MECHANISM

Alwin Leopold Huehn, Milwaukee, Wis., assignor to Square D Company, Detroit, Mich., a corporation of Michigan

Application March 23, 1953, Serial No. 344,147

6 Claims. (Cl. 292—7)

This invention relates to a mechanism which interlocks the door locking mechanism of a cabinet with exteriorly manipulated mechanism for operating a device such as an electric circuit breaker or switch mounted within the cabinet.

An object of the invention is to provide a simple, rugged and inexpensive interlock mechanism between the operating mechanism of a device enclosed within a cabinet and the locking mechanism for the door of the cabinet.

Another object of the invention is the provision of an interlock mechanism in accordance with the preceding object in which it is impossible to jam the mechanism by a simultaneous manual manipulation of the door and device operating handles.

Another object of the invention is an interlock mechanism in accordance with the preceding objects in which any number of devices may be interlocked with the door locking mechanism and in which the devices may be located in various locations relative to the door with simple adjustments.

Other objects and features of the invention will be readily apparent to those skilled in the art from the specification and appended drawings illustrating certain preferred embodiments in which:

Figure 1 is a partial front elevational view of a cabinet door showing exterior handles for manipulation.

Figure 2 is an internal perspective view of the interlock mechanism with the parts shown with the interlock disabled.

Figure 3 is a figure similar to Figure 2 with the interlock mechanism in operative position.

Figure 4 is a perspective view showing the interlock mechanism in a second operative position.

The interlock mechanism of the present invention is applied to a conventional cabinet 1 having a hinged front door 2 provided at the exterior thereof with front manipulable handles 3 and 4, the handle 3 operating the door locking and unlocking mechanism and the handle 4 operating a device such as an electric circuit breaker or disconnect switch within the cabinet. The handle 4 is provided with a hub 5 having slots in its side walls into which may be inserted a locking bar 6 to lock the handle in various positions.

The handle 3 is mounted on a shaft 7 extending through the door 2 and carrying at the back of the door a latch member 8 connected to a pair of oppositely directed shoot bolts 9 and 11 adapted to engage the cabinet adjacent the top and bottom of the door opening to latch door closed. Latch member 8 has a rigid arm 12 mounted thereon in a position to cooperate with a latch 13 adjustably mounted on a pivoted lever 14. On the back wall of the door 2 is mounted a four-sided bracket 15 having the lever 14 pivoted in its opposite side walls. A bracket 16 is mounted on one side wall of the bracket 15 and a rod 17 extends through openings in the bracket 16 and in the top wall of the bracket 15, being thus guided for rectilinear movement in a substantially vertical direction as shown. A spring 18 biases rod 17 in the downward direction to en-

2

gage the lower end of the rod with an arm 19 on the lever 14.

The rod 17 extends through an opening in a flange 21 integral with one arm of a bell-crank lever 22 pivoted at 20 on the back of the door. The flange 21 engages an adjustable stop 10 on the rod 17 in one direction. A lever 23 is pivoted intermediate its ends at 24 on the back of the cover 2 and is guided for limited rotary movement in a plane parallel to the door by a bracket 25. A spring 26 between the lever 23 and bracket 25 biases the lever for rotation in a counterclockwise direction as viewed in the drawings. A pair of angle brackets 27 and 28 are pivotally mounted on the levers 22 and 23 and are interconnected by means of a rod 29 adjustably engaging therewith.

The interlock mechanism has been shown in a cabinet containing an electric circuit breaker 31 having suitable operating mechanism interiorly and exteriorly of its casing, this including a rotatable operating shaft 32 terminating at its outer end in a male member 33 adapted to cooperate, when the door 2 is closed, with a female socket 34 rigidly mounted upon the shaft carrying the handle 4. Also mounted on this shaft is an arm 35, the handle 4, socket 34 and arm 35 being rigidly connected together for movement as a unit. The arm 35 is provided adjacent its end with a roller 36 adapted to cooperate with a cam surface 37 located on a lower edge of the lever 23. The cam surface 37 is provided with an indexing notch 38 engaged by the roller 36 in the position of the parts shown in Figure 2.

The operation of the interlock mechanism will now be described:

With the door 2 closed, the socket 34 engages the male member 33 so as to join the exterior handle 4 to the shaft 32 to effect rotation thereof and operation of the mechanism within the circuit breaker 31. The parts as shown in Figure 3 are in the position with the circuit breaker On to close the circuit therethrough. In this position, the handle 4 has been rotated into its farthest counterclockwise position, as viewed in Figure 1, which moves the circuit breaker operating means shown in Figures 2 through 4 to their farthest clockwise position, this being shown in Figure 3 where the roller 36 on the arm 35 has been rotated to a position where it entirely disengages the cam 37 on the lever 23. The lever 23 has thus been freed to move in a counterclockwise direction under the bias of the spring 26, its ultimate position being limited by the bracket 25. As the lever 23 moved to its counterclockwise position, the bell-crank lever 22 rotated in a clockwise direction and the rod 17 was raised by the engagement of the flange 21 with the stop 10 on the rod, the spring 26 being sufficiently strong relative to spring 18 to accomplish this movement. In the upward position of the rod 17, the lever 14 rotated into locking position under either the bias of gravity or the bias of a spring, not shown, which may be used if desired where the bias of gravity is not effective. With the parts in the position described, the arm 12 engages with the latch 13 if the door handle is manipulated, thus preventing rotation of the latch member 8 and preventing withdrawal of the shoot bolts 9 and 11.

When the operating handle 4 is moved to the Off position, the parts assume the position shown in Figure 2 with the roller 36 engaged in the indexing notch 38 on the lever 23. This rotation of the arm 35 to index the roller and notch rotates the lever 23 in a clockwise direction against its bias and rotates the bell-crank 22 in a counterclockwise direction, freeing the rod 17 for movement downwardly under the bias of its spring 18. As the rod moves downwardly, its lower end engages the arm 19 on the lever 14 and rotates the lever in a counterclockwise direction away from the door and against the biasing force

of gravity or its spring, if used. In this lower position of the rod 17, the latch 13 has been moved out of obstructing relation to the arm 12 and the handle 3 may be freely rotated to rotate the latch member 8 and retract the shoot bolts 9 and 11 to permit the door 2 to be opened, this opening movement disengaging socket 34 from male member 33.

In the operation of devices within the cabinet, the handle 4 may assume a position beyond the Off position, which third position may in the case of electric circuit breakers be utilized to effect a resetting of the mechanism after an automatic trip. In this third position of the handle the circuit breaker contacts are maintained disengaged and the roller 36 has been moved below the notch 38 as shown in Figure 4. In this position of the handle, the lever 23 has rotated in a counterclockwise direction sufficiently to move the rod 17 upwardly to permit the lever 14 to swing toward the door under its bias.

This again places the latch 13 in obstructing position with respect to the arm 12 and if the handle 4 is locked in this third or resetting position, the circuit breaker contacts will be maintained Off while the cabinet door is locked closed.

With the interlock mechanism of the present invention, it is seen that should the door handle be left in the open position when the circuit breaker is moved closed, the door handle will lock automatically thereafter as it is turned to closed position, the lever 14 swinging away from the door to permit passage of the arm 12 as the lower edge of the arm engages the inclined edge of the latch 13.

It is further seen that with the provision of operation of the latch 13 and lever 14 through the spring 18 which overcomes the bias on the lever 14, no jamming can occur from forcing the exterior operating handles. It is also seen that a number of mechanisms may be mounted to cooperate with the rod 17 and it will be necessary for all of the devices associated with the mechanisms to be in Off position before the rod 17 will be permitted to move downwardly to disable the interlock.

Also, it is seen that the location of the device within the cabinet and adjustments for inaccuracies may be readily made through a simple variation in the effective lengths of the rods 17 and 29.

While certain preferred embodiments of the invention have been specifically disclosed, it is understood that the invention is not limited thereto, as many variations will be readily apparent to those skilled in the art and the invention is to be given its broadest possible interpretation within the terms of the following claims:

What is claimed is:

1. An interlock between door locking mechanism and operating mechanism for a device installed behind the door comprising door locking mechanism behind the door, an operating handle on the front of the door for operating said door locking mechanism, a second operating handle on the front of the door for operating a device installed behind the door, a latch mounted on the back of the door and biased into a position obstructing unlocking movement of the door locking mechanism, a member mounted on the back of the door and biased to move said latch against its bias into non-obstructing position, a lever pivoted at the back of the door and engaging said member in one direction only to move it against its bias, a second lever pivoted on the back of the door and biased to move said first lever in a direction to move the member against its bias, and means for moving said second lever against its bias in response to movement of the device operating handle so as to effect movement of said latch into obstructing and non-obstructing position in response to the chain of movement through said device operating handle, second lever, first lever, and member.

2. An interlock as defined in claim 1 in which the point of engagement of the first lever and member is adjustable to compensate for variation in the relation of the device and door locking member.

5 3. An interlock between door locking mechanism and operating mechanism for a device installed behind the door comprising door locking mechanism behind the door, an operating handle on the front of the door for operating said door locking mechanism, a second operating handle on the front of the door for operating a device installed behind the door, a latch mounted on the back of the door and biased into a position obstructing unlocking movement of the door locking mechanism, a member mounted on the back of the door and biased to move said latch against its bias into non-obstructing position, a lever pivoted on the back of said door and operable to move said member against its bias and means responsive to rotation of said device operating handle for rotating said lever to move the member to effect movement of the latch into and out of obstructing position.

4. An interlock mechanism for the door of an enclosing cabinet having means at the exterior of the door for operating a device enclosed within the cabinet including manipulable means at the exterior of the door for effecting operation of the door-locking mechanism disposed behind the door, a latch pivoted on the back of the door and rotatable toward and away from the door into and out of position obstructing the unlocking movement of the door locking mechanism, a reciprocal rod biased to rotate said latch away from the door into unlatching position, said rod being guided for rectilinear movement parallel to the door and provided with biasing means for moving it toward latch disengaging position, said rod engaging the latch only in its biased direction, a first lever pivoted at the back of the door and engaging said rod in one direction only to move it against its bias, a second lever pivoted at the back of the door, means interconnecting said levers, means biasing said second lever to rotate said first lever in a direction to move the rod against its bias, manipulable means at the exterior of the door and extending thereto to effect operation of a device within the cabinet, and an arm rotatable by said manipulable means in a plane parallel to the door and engaging said second lever to effect movement thereof against its bias to enable the rod to move under its bias to disable the latch and permit unlocking movement of the door locking mechanism.

50 5. An interlocking mechanism defined in claim 1 in which the arm is provided with a roller engaging a cam surface on said lever to effect movement thereof against its bias, the cam surface including an indexing notch receiving the roller to hold the manipulable means in an indexed position corresponding to the latch disabled position of the interlock mechanism.

55 6. An interlocking mechanism as defined in claim 4 in which the engagement between said rod and first lever is adjustable and the connecting means between said first and second levers is adjustable whereby to compensate for variations in the locations of the device and door locking mechanisms.
